Filed May 10, 1971, Ser. No. 142,099

Term of patent 14 years

Int. Cl. D6—03

U.S. Cl. D6—149

The figure is a perspective view of a table showing my new design, it being understood that the sequence of alternating wood-like and patterned translucent panels is repeated on the unseen portion.

The figure shows patterns in alternate, translucent side panels which are visible when the table is lighted internally.

I claim:

The ornamental design for a table, substantially as shown and described.
